UNITED STATES PATENT OFFICE.

EDWIN THORN, OF UTICA, NEW YORK.

MATCH.

SPECIFICATION forming part of Letters Patent No. 781,972, dated February 7, 1905.

Application filed October 1, 1904. Serial No. 226,869.

To all whom it may concern:

Be it known that I, EDWIN THORN, a citizen of the United States, residing at Utica, in the county of Oneida and State of New York, have 5 invented certain new and useful Improvements in Matches; and I do hereby declare the following to be a full, clear, and exact description of the invention, such as will enable others skilled in the art to which it appertains to 10 make and use the same.

This invention relates to improvements in matches, and particularly to the flexible type.

The object in view is the production of a match susceptible of assuming a compact form 15 and being readily ignited.

With this and further objects in view the invention comprises a flexible strip of material and igniting means at various points intermediate the length of said strip and means 20 contiguous to each of said igniting means for effecting ignition thereof.

It further comprises certain other novel constructions, combinations, and arrangements of parts, as will be hereinafter fully described 25 and claimed.

In the accompanying drawings, Figure 1 represents a top plan view of a strip of material embodying the features of the present invention. Fig. 2 represents an edge view 30 thereof. Fig. 3 represents a top plan view of a slightly-modified form of the same. Fig. 4 represents an edge view of the structure disclosed in Fig. 3. Fig. 5 represents a top plan view of a further modification. Fig. 6 represents an edge view of the same. Fig. 7 represents a view in side elevation of a coil of 35 matches embodying the present invention.

In carrying out the present invention I preferably embody the same in the form, as 40 seen particularly in Figs. 1, 2, and 7, of a continuous strip 1 of inflammable flexible material of suitable width and folded at various points intermediate its length. Each of the 45 said folds consists, preferably, of a bent or lapped-over portion 2, adhered, as at 3, to the main portion of the strip 1, and a further bent portion 4, extending past the bent portion 2, the continuation of the portion 4 constituting the remainder of the strip 1. The 50 strip is preferably scored or weakened, as at

5, at the point of the bend between the portion 2 and the portion 4. The lap 2, as will be seen in the drawings, is bent back upon the strip 1 and at its forward end is provided with a rubbing-surface 6, which may consist 55 of a roughened portion, as sandpaper, or of a well-known rubbing compound. At the rear end of the portion 4, upon its upper surface, as at 7, is provided an igniting compound, which is adapted when brought into 60 contact with the rubbing-surface 6 with sufficient velocity to ignite either from the friction alone or by the compound of chemicals, according to the nature of igniting material employed. As many of the laps 2 and return 65 portions 4 may be formed in the length of the strip 1 as may be desired, or, in other words, the length of each match may be whatever required and is determined by the distance 70 between the several laps 2.

In operation the strip 1 when completed, as above described, is preferably rolled into a disk, as seen in Fig. 7, and when it is desired to utilize one of the matches it is only necessary to grasp the disk, pressing the strip 1 75 just above the outermost lap 2, and pull upon the projecting end of the strip 1. The strain upon the projecting end produces a severance at the score 5, and as the igniting material 7 passes the rubbing-surface 6 ignition occurs 80 and the match is ready for use. A second operation may be performed in exactly the same manner.

It will thus be seen that the strip 1 is divided into a plurality of sections of strip, each capable of use independently as a match, and the front end of each is overlapped by an overlapping portion or flap from and carried by the preceding strip.

In Figs. 3 and 4 I have illustrated a slightly- 90 modified form of the present improved match, which consists of a strip of flexible inflammable material 8, which is made up of a number of relatively short sections 8' 8', each of the sections 8' being secured at one end to the 95 preceding sections, the other end of course being secured to the succeeding section. At the forward end of each section 8' is provided igniting material 9, lying beneath the overhanging end 10 of the next preceding section, 100

the said overhanging end 10 being provided on its under surface with a rubbing-surface 11. The strip 8 may be rolled as described with respect to strip 1 and operated upon in substantially the same manner, the projecting end 5 of the first section 8' being grasped while the upper surface of the overhanging portion 10 is pressed by the finger, and the strain upon the projecting portion of the first section 8' 10 will cause its severance from the preceding section, and longitudinal movement of the first section will cause igniting contact of the material 9 with the surface 11. The only material difference between the structures seen 15 in Figs. 1 and 2 and disclosed in Figs. 3 and 4 lies in the fact that the first-mentioned disclosure embodies a continuous unbroken strip folded at various points, and the second-mentioned disclosure embodies a succession of 20 sections of strip secured together in such manner that their ends overlap.

In Figs. 5 and 6 I have disclosed a further modification of the present invention, which involves a strip 12 made up of a succession of 25 relatively short sections of strip 12' 12", each of the said sections being connected to the preceding section by a strip 12''. Each strip 12'' thus is adhered to the front end of one of the sections 12' and to the rear end of the next 30 preceding section 12'. At the rear end of each of the sections 12'' is provided suitable igniting material 13, arranged, preferably, on the under surface of said section, and each of the strips 12'' is formed with an overhanging portion 14 extending beyond and forwardly of the material 13, the front end of each of the overhanging portions 14 being provided 35 with a rubbing-surface 15, adapted in operation to be engaged by the igniting compound 40 13 when the section 12' is severed from the strip 12'' and moved longitudinally, which severance and longitudinal movement effect ignition of the section. Each section 12' may 45 be provided with scoring or otherwise suitably weakened at the point of severance for facilitating its disconnection from the strip 12."

Having thus fully described my invention, what I claim as new, and desire to secure by Letters Patent, is—

50 1. A device of the class described comprising a strip of material, igniting means carried thereby at various points intermediate the length thereof, and means carried by the strip contiguous to said igniting means for 55 effecting ignition thereof.

2. A device of the class described, comprising a strip of flexible material adapted to be wound into a roll, igniting means at various points intermediate the length of said strip, and means carried by the strip for effecting 60 ignition of the igniting means.

3. A strip of match material, comprising a plurality of sections, an overlapping portion carried by one section and overhanging the other, and igniting means and means for effecting ignition arranged one on the overlapping portion and the other on the section. 65

4. A match-strip comprising a plurality of sections of strip, a flap or overhanging portion carried by one of said strips and overlapping the other, a rubbing-surface carried by said flap, and igniting means carried by the section of strip overlapped by the flap. 70

5. A match-strip, comprising a plurality of sections, each provided with an overlapping portion overhanging the preceding section, and igniting means and means for effecting ignition arranged one on the overlapping portion and the other on the section of strip overlapped. 75

6. A match-strip comprising a plurality of sections of strip, igniting means carried by each of said sections, a flap overhanging said igniting means, and means carried by said flap for effecting ignition of the igniting means. 80 85

7. A match-strip, comprising a plurality of independent sections attached together, each with its rear end overlapping the front end of the preceding section, igniting means and means for effecting ignition thereof arranged 90 one on the overhanging portion of each section and the other at the opposite end thereof.

8. A match-strip comprising a plurality of sections secured together in endwise relation, igniting means carried by each of said sections 95 of strip near one end thereof, a flap overhanging said igniting means, and a rubbing-surface carried by said flap.

9. A match-strip comprising a continuous strip of flexible material folded back upon 100 itself at a plurality of points, and igniting means and means for effecting ignition thereof carried at the point of each of said folds.

In testimony whereof I hereunto affix my signature in presence of two witnesses.

EDWIN THORN.
